UNITED STATES PATENT OFFICE.

CHARLES W. PARSONS, OF WASHINGTON, DISTRICT OF COLUMBIA.

COMBINED CONCRETE MIXING AND ELEVATING APPARATUS.

1,209,483.

Specification of Letters Patent. Patented Dec. 19, 1916.

Application filed March 18, 1916. Serial No. 85,171.

To all whom it may concern:

Be it known that I, CHARLES W. PARSONS, a citizen of the United States, residing at Washington, in the District of Columbia, 5 have invented certain new and useful Improvements in Combined Concrete Mixing and Elevating Apparatus, of which the following is a specification.

This invention relates to a combined mixing and elevating apparatus which has for its object the provision of means in the nature of an elevator or hoist, the hoisting elements thereof constituting concrete mixers arranged in such manner that they may be automatically rotated to mix the concrete during the ascent of the hoist or arranged in such manner that they may be driven to mix the concrete when the hoist is at rest and the concrete mixer is being 20 filled.

Further objects and advantages of the invention will be set forth in the detailed description which now follows:

In the accompanying drawings: Figure 1 25 is a side elevation of the combined hoisting and mixing apparatus constructed in accordance with the present invention; Fig. 2 is a side elevation of one of the concrete mixers and the frame in which it is mounted; Fig. 3 is a horizontal sectional view upon line 3—3 of Fig. 2; Fig. 4 is a vertical sectional view through one of the frames, illustrating the manner in which the concrete mixer tips to discharge its load.

Referring to the drawing, the numerals 5 30 designate the vertical members and 6 the horizontal members of a tower. Mounted to travel vertically in this tower are two cages 7 and 8. These cages are connected by 35 a cable 9 which passes directly from one of said cages and over pulleys 10 and 11 to the other of said cages, whereby these cages are always held in a definite and spaced relation to each other and one of said cages counter- 40 balances the other, so that the hoisting engine or other motor has only to lift the weight of the concrete. Trunnioned in each 45 of the cages 7 and 8 is a tilting frame 12, the mounting of said frames in the cages 50 being through the medium of a stub shaft 13 and a shaft 14. Grooved pulleys 15 are secured to the shafts 14. The shafts 14 carry beveled pinions 16 which mesh with beveled toothed rings 17 upon drums 18 in

which the concrete is mixed during the rotation of said drums. Concrete mixers of this general type are very well known and require no further description. The frames 12 comprise forwardly and rearwardly extending portions 19 which carry beveled rollers 20, said rollers serving to support the drums 18. It will therefore be seen that the drums are capable of rotation and that when the frames 12 are tilted, the contents of the drums may be discharged from the open 65 ends thereof, in the usual manner. The meshing of the pinion 16 and the gear ring 17 during the tipping operation is maintained because the frames swing about the center about which the pinions rotate. 70 Those portions of the frame 12 lying above and below the grooved pulleys 15 are extended to form yokes 21 and 22 which permit tilting of the frame 12 without interference from the driving cables hereinbefore 75 described.

As is well known, the ordinary hoisting engine comprises a pair of drums either of which may be independently driven. Such a hoisting engine has been indicated in a 80 general way at 23 in Fig. 1. The shaft 24 of one of the drums of this hoisting engine is provided, according to the present invention, with a grooved pulley 25 over which a hoisting cable 26 passes. One end of this 85 hoisting cable passes over a pulley 28, then extends vertically and passes over pulleys 29 and 30 and is connected to the cage 8. The other portion of this cable 26 passes over a pulley 31, then extends vertically, passes over 90 pulleys 32 and 33 and its end is connected to the cage 7. It will therefore be seen that when the pulley 25 is rotated in one direction or the other the cages 7 and 8 will be alternately raised and lowered. Another 95 cable which I term the driving cable, is indicated at 34. The bight of this cable passes over one of the drums of the hoisting engine indicated at 35, though it is to be understood that it may pass over a grooved pulley fast 100 upon the shaft of said drum. These drums are equipped with brakes as is well-known and I have indicated the brake handle at 36 in Fig. 1. One side of this cable 34 passes over a pulley 37, thence vertically through 105 the yokes 21 and 22, takes a turn about one of the pulleys 15, thence passes over pulleys 38 and 39, thence extends downwardly, passes

over pulleys 40 and 41 thence extends vertically passing through the yokes 21 and 22 of the other cage, takes a turn about pulley 15 in said cage, thence passes over pulleys 42 5 and 43, thence downwardly and over a pulley 44 and back to the drum 35. It will therefore be seen that if rotation is imparted to the drum 35 to drive the cable 34, rotation will be imparted to the pulleys 15, shafts 14, 10 pinions 16 and drums 18. It will further be seen that if the brake 36 is applied to the drum 35 and said drum is held against rotation during the time that the hoisting cable 26 is hoisting the cages, the pulleys 15 will, 15 under these circumstances, be likewise rotated to drive the concrete mixers. Therefore, when one of the cages is discharging its load at the top of the tower and said cage is at a stand-still, the concrete mixer may be 20 driven and the material that is being placed in the concrete mixer at the bottom of the tower may be in process of being mixed. In addition the mixing operation is continued throughout the ascent of the cages. It is ap- 25 parent, therefore, that much time, labor and expense will be saved by virtue of the construction herein shown and described, because the material need be handled but once from the time that it is in its separate form 30 to the time that it is delivered mixed ready for use at the top of the building. Even the time ordinarily employed in transit of the material from the ground to the top of the tower is utilized to mix the material during 35 such transit.

While the exemplification of the invention illustrated in the accompanying drawings discloses a structure adapted to secure the desired result, I am aware that in the 40 wide field of mechanics other ways may readily be resorted to to accomplish the ends sought and it is to be understood that the invention is not limited to the particular form of the apparatus shown, but that it in- 45 cludes within its purview whatever changes fairly come within the spirit of the appended claims.

Having described my invention what I claim is:

1. The combination with a tower, of a pair 50 of cages mounted therein, means for connecting said cages so that they counterbalance each other, means for alternately raising and lowering said cages, a concrete mixer in each of said cages, a rotative element for each of said concrete mixers and through which movement is imparted to said mixers, a driving cable passing through each of said elements, means for driving said cable and means for holding said cable 55 against movement, whereby when the cages are being raised and lowered their respective concrete mixers are driven by the movement of said concrete mixers with relation to said driving cable and said concrete mixers may 60 be driven when the cages are at rest, by the bodily movement of the driving cable.

2. In a device of the character described, the combination with a tower, of a pair of 70 cages mounted therein, and connected to counterbalance each other, a concrete mixer carried by each of said cages, a driving cable connected to said concrete mixers, and common to both of them and a lifting cable connected to said cages and common to both of 75 them and means for driving said cables.

3. In a device of the character described, the combination with a tower, of a pair of cages mounted therein and connected to counterbalance each other, a concrete mixer 80 carried by each of said cages, a driving cable connected to said concrete mixers and a lifting cable connected to said cages, and means for holding the driving cable against movement during the movement of the cages to 85 thereby cause said driving cable to drive the concrete mixers through the bodily movement of the cages with relation to said cable and means for driving the driving cable to cause it to drive the concrete mixers inde- 90 pendently of the bodily movement of the cages.

In testimony whereof I affix my signature.
CHARLES W. PARSONS.
